Attorneys.

UNITED STATES PATENT OFFICE.

CLARENCE W. BURGER, OF WASHINGTON, DISTRICT OF COLUMBIA.

CONTACT DRUM AND METHOD OF MAKING THE SAME.

Application filed December 14, 1921. Serial No. 522,424.

To all whom it may concern:

Be it known that I, CLARENCE W. BURGER, a citizen of the United States, residing at Washington, District of Columbia, have invented certain new and useful Improvements in Contact Drums and Methods of Making the Same, of which the following is a specification.

This invention relates to contact drums such as are adapted to co-operate with resilient fingers or brushes for the purpose of controlling electric circuits.

In Patent No. 1,394,768, granted October 25, 1921, to J. E. Smith and myself, there is shown a somewhat similar contact drum, and an apparatus in which it may be advantageously employed.

Although the present invention may be considered as a specific improvement over the above patent, and as especially designed for use in connection with automatic transmitters for teaching telegraphic codes, it will be understood that, in its broader aspects, the invention relates to contact drums for any purpose whatsoever, such, for example, as for controlling motors, flashing electric signs, etc.

The object of the invention is to provide a practical and effective method of manufacturing such drums more cheaply than has heretofore been possible, and to produce an article which will be strong, durable, efficient and reliable in service.

To this end, I propose to build up a contact drum from a series of discs and spacing elements, with insulating material filling the space between the discs, and being dressed off to form a smooth cylindrical surface.

In order that the invention may be readily understood, reference is had to the accompanying drawing forming a part of this specification, and in which:

Fig. 1 is a side view of a contact drum constructed in accordance with the invention.

Fig. 2 is a central transverse section through the same.

Fig. 3 is a similar sectional view but illustrating the elements of the drum in their separated condition before being assembled, and

Fig. 4 is a fragmentary sectional view on an enlarged scale showing certain details of construction and illustrating the method of applying the insulating material.

Referring to the drawing in detail, my im-

proved drum comprises a series of parallel metallic discs, the two outside ones of which are designated as 1 and 2 respectively. These outside discs are preferably of the form shown in Fig. 1, that is to say, they are complete wheels having openings 3 formed through them.

Passing centrally through the discs 1 and 2 and rigidly secured thereto is a hollow shaft 4 which is somewhat longer than the distance between the discs 1 and 2, and projects beyond the disc 1 as shown in Fig. 2. To the projecting end of this hollow shaft 4 is secured a gear wheel 11 by means of which the drum is rotated. The two discs 1 and 2 are properly spaced at the center by means of a sleeve 5 surrounding the shaft 4, and the wheel 11 is spaced from the disc 1 by means of a similar though shorter sleeve 10.

The discs are also secured together and held in assembled relation by means of hollow rivets 6, as clearly shown in the drawing, such rivets being preferably located near the periphery of the discs as will hereinafter appear.

Located between the outside discs 1 and 2 is a series of intermediate annular elements 7, of the same outside diameter as the discs 1 and 2. These elements 7, so far as the operation of the contact drum is concerned, might be complete discs similar to 1 and 2, but for the sake of cheapness and lightness, the interior of these elements is cut away, thus leaving only comparatively narrow flat rings, as clearly shown in Figs. 3 and 4. For the sake of simplicity, however, these annular elements will be referred to throughout the specification and claims as "discs," and it will be understood that this word is intended to include annular rings, as well as complete discs.

The annular discs 7 above described, are provided with openings 7^a corresponding in number and position to the hollow rivets 6, so that, when the parts are assembled, these rivets pass through the elements 7 as well as the discs 1 and 2.

Located between the discs 1 and 2, and the annular elements or discs 7 themselves, are a series of spacing elements 9. These are preferably in the form of wire rings of a diameter slightly greater than that of the circle on which the rivets 6 are set, so that these rings snugly encircle or embrace the rivets.

When the parts are assembled as shown in

Fig. 2, it will be seen from an inspection of Fig. 4, that annular grooves 8 are formed between the several discs and that the spacing rings 9 constitute the bottom of such 5 grooves.

It will be understood that the peripheries both of the discs 1 and 2 and also the annular discs 7 are cut or shaped to form notches and teeth, the latter constituting 10 the contact points. If the drum is employed as a telegraph transmitter, the general appearance of these teeth and notches is indicated in Fig. 1, the teeth being designated at 12, and the notches at 13. As 15 shown, these teeth and notches are of varying lengths so as to give rise to the familiar dots and dashes of a telegraph code. If on the other hand the contact drum be designed for use as a motor controller, a sign 20 flasher, or for other purposes, the peripheries of the discs will be correspondingly varied, and it will be understood that by 25 the term "teeth" as employed in the claims, I intend to include any projection or formation whatsoever carried by the peripheries of the discs, even though such projection should extend for a large portion of the circumference.

Having assembled the discs and spacing 30 rings, with the grooves 8 between the discs, as shown at the right in Fig. 4, I next fill such grooves, as well as the spaces or notches between the teeth or projections, with plastic insulating material such as indicated at 35 x in Fig. 4. The material which I prefer to employ is raw rubber. After having filled all of the grooves and notches with this material, it is subjected to a hardening process, as by vulcanizing. After the insulating material is thus hardened or vulcanized, the drum, having a more or less 40 irregular surface as indicated in Fig. 4, is placed in a lathe or the like and "turned," the tool being adjusted so as to dress the periphery of the drum to a true smooth 45 cylindrical surface as indicated by the line $y-z$ in Fig. 2, with the teeth or projections 12 extending through the insulating material and terminating flush with such 50 smooth cylindrical surface.

Since, as will be readily understood, the discs 1, 2 and 7 can be readily punched from sheet metal, and easily assembled in the manner described, it will be seen that 55 I have provided an exceptionally cheap and effective method of forming contact drums, and it will also be observed that the finished drum has a smooth cylindrical surface, composed partly of insulating material and partly of metallic contacts, such 60 drum having all the advantages of those heretofore constructed by more tedious and expensive methods.

What I claim is:

1. A contact drum comprising a plural- 65 ity of parallel metallic discs having peripheral teeth, spacing rings between the discs, means for holding said rings and discs in assembled relation, said rings being of smaller diameter than said discs, whereby 70 annular grooves are formed outside of said rings between said discs, and insulating material filling said grooves and the spaces between said teeth, and terminating flush with the ends of said teeth. 75

2. A contact drum comprising a series of 80 conducting discs, conducting spacing elements between said discs, and means for holding said discs and spacing elements in assembled relation.

3. A contact drum comprising a series of 85 conducting discs, conducting spacing elements between said discs, and hollow rivets for holding said discs and spacing elements in assembled relation.

4. A contact drum comprising a series of 90 assembled, parallel discs, spacing elements between said discs, and a hollow shaft extending centrally through said discs and secured to the two outer ones only, the intermediate discs being cut away at their centers so as not to engage said shaft.

5. A contact drum comprising a pair of 95 outer metallic discs and a plurality of intermediate annular metallic plates, said discs and annular plates being assembled in spaced parallel relation to form a cylindrical structure having a hollow interior, the peripheries of said plates and discs being provided with teeth, forming contacts. 100

6. The method of making a contact drum 105 which consists in assembling a series of metallic discs, each having teeth on its periphery, in parallel spaced relation, filling the spaces between the outer portions of said discs and between said teeth with plastic insulating material, hardening said material, and finally dressing off the periphery of the drum to form a smooth cylindrical surface, with the ends of said teeth terminating flush with such surface. 110

7. The method of making a contact drum 115 which consists in assembling a series of parallel metallic discs with a series of spacing rings of smaller diameter, the rings and discs being alternately arranged so that annular grooves between the discs are formed, the rings constituting the bottom of said grooves, filling such grooves with plastic insulating material, hardening said material, and then dressing off the material to form a smooth cylindrical surface with portions of the periphery of said discs projecting therethrough. 120

In testimony whereof I affix my signature.
CLARENCE W. BURGER.
